(57) **CLAIM**

The ornamental design for a sole, as shown and described.

DESCRIPTION

The file of this patent contains at least one photograph executed in color. Copies of this patent with color photographs will be provided by the Office upon request and payment of the necessary fee.

FIG. 1 is a front side perspective view of a sole showing the claimed design;

FIG. 2 is a rear side perspective view thereof; and,

FIG. 3 is a side view thereof.

The dot-dash broken lines in the figures and the whited out areas within the dot-dash broken lines show portions of the sole and environment that form no part of the claimed design.

FIGS. 1-3 are illustrated with pink, red, and gray to show a transparent appearance. No particular color is claimed.
